UNITED STATES PATENT OFFICE.

ALEXANDER GRANT COLE, OF OTTAWA, ONTARIO, CANADA.

FOLDABLE FRAME FOR CHAIRS, TABLES, OR THE LIKE.

1,027,692.

Specification of Letters Patent.

Patented May 28, 1912.

Application filed November 9, 1909. Serial No. 527,077.

To all whom it may concern:

Be it known that I, ALEXANDER GRANT COLE, a subject of the King of Great Britain, and residing at No. 142 McLaren street, in 5 the city of Ottawa, in the Province of Ontario, in the Dominion of Canada, have invented certain new and useful Improvements in Foldable Frames for Chairs, Tables, or the Like, of which the following is a 10 specification.

The invention relates to improvements in foldable frames for chairs, tables or the like, as described in the present specification and illustrated in the accompanying drawings 15 that form part of the same.

The invention consists essentially of the novel arrangement and construction of parts, whereby crossed bars are pivotally secured at the juncture thereof in pairs and 20 hinged at the extremities thereof to side bars, and having reinforcing members secured at the juncture thereof to support the bars in their spread position, whereby they may be folded substantially parallel and 25 close one with the other.

The objects of the invention are to devise a supporting-frame for a chair, table or the like, which will be inter-connected to form a very rigid and durable frame-work of 30 exceedingly light construction, so that the chair, table or other article of furniture having a frame as hereinafter described may be readily folded into a very small compass and carried from one place to another.

In the drawings, Figure 1 is a perspective view of the frame in its set-up position. Fig. 2 is a perspective view of the frame with the cover secured thereon to form a 40 complete chair. Fig. 3 is a perspective view of the frame partially folded. Fig. 4 is a plan view of the joint members at the juncture of the crossed bars forming the front of the chair. Fig. 5 is a plan view of 45 the joint member at the juncture of the crossed bars forming the back of the chair. Fig. 6 is an enlarged perspective view of a corner hinge member at the extremities of a crossed bar. Fig. 7 is an enlarged sectional perspective view of the corner hinge member used for connecting the back-piece of the chair. Fig. 8 is an enlarged perspec-

tive detail view of one end of the back-piece and the locking-plate thereof.

Like numerals of reference indicate corresponding parts in each figure.

Referring to the drawings, 1 are front bars pivotally secured one to the other midway of their length by the pivot-pin 2, said bars 1 forming the front of the chair frame. 60

3 are plates having the center orifice 4 therethrough and secured by the pivot-pin 2 between the bars 1.

The plates 3 are substantially S-shape, and have the lugs 5 projecting outwardly 65 therefrom to either side of the bars 1, whereby said plates 3 are firmly clamped against the bars 1, and the lugs 5 form a substantial support for the side bars and materially strengthen the same. 70

6 are lugs projecting from the plates 3 on the opposite side to the lugs 5, and as the plates 3 are immediately next one another between the meeting faces of the bars 1, the lugs 6 of one plate will contact with the lugs 75 6 of the other plate when the bars 1 are extended, as shown in Figs. 1 and 4. The bars 1 are thus firmly supported in their extended position from collapsing.

7 are back bars pivotally secured one to 80 the other intermediate of their length by the pivot-pin 8, said bars forming the back of the chair frame.

9 is a plate having the central orifice 10 therethrough and interposed between the 85 bars 7 where they are pivotally connected by the pivot-pin 8.

The plate 9 has the lugs 11 projecting from one side thereof next to the alternate sides of one of the bars 7, said plate being 90 firmly secured to the bar by wood-screws 12 inserted through suitable orifices toward each end of the said plate, so that said plate turns with one bar 7 against the side of the other bar 7 of the pair. 95

13 are lateral arc-shaped extensions from the plate 9, and 14 are stop lugs projecting from the extensions 13 and engaging with the bar 7 which turns on the plate, when the frame of the chair is set up, said stop lugs 100 14 forming a substantial support for the back bars 7.

15 are side bars having the slots 18 at the ends thereof and hinged by the joint mem-

ber hereinafter described with the lower ends of the front bars 1.

16 are hinge knuckles having the pins 17 projecting therefrom.

5 The knuckles 16 are inserted in the slots 18 in the lower ends of the side bars 15, pins 19 being inserted through orifices in the lower ends of the side bars 15 and a central orifice in the hinge knuckle 16, and firmly 10 securing the hinge knuckles in the slots at the ends of said side bars 15.

20 are washers on the sides of the bar 15 where the pins 19 extend therethrough to prevent the said bar from splitting.

15 The pins 17 projecting from the hinge knuckles 16 are inserted through orifices at the lower ends of the bars 1 and riveted, the washers 21 being provided on said pins to the outer side of the bars 1 in order to prevent their splitting.

The side bars 15 are hinged at the top thereof to the tops of the back bars 7 by the hinge knuckles 22 similar to the hinge knuckles 16.

25 23 are seat bars, hinged at the outer end thereof to the upper ends of the front bars 1 by the hinge knuckles 24 similar to the knuckles 16. The seat bars 23 at their inner ends are pivotally secured to the side bars 15 30 intermediate of their length by the pivot-pins 25.

26 are foot bars hinged at their lower ends by the knuckles 27 with the lower ends of the back bars 7, and pivotally secured at 35 their upper ends to the side bars 15 by the pivot-pins 28 immediately below the pins 25, plates 29 being secured over the bars 23 and 26 where they are pivotally secured to the bar 15 by the pins 25 and 28.

40 30 is a connecting-bar extending between the back bars 7 at the upper end thereof, and having one end riveted on to the pin extending from the hinge knuckle 22, said pin being of sufficient length to extend through 45 the bar 7 and also the bar 30. The back bar 30 at the other end thereof has the plate 31 secured thereto on the inner side, said plate having the slot 32 enlarged at 33 at the inner end thereof, and having the notch 34 at 50 the outer end thereof.

As above mentioned, the pin extending from one of the hinge knuckles 22 at the top of one of the bars 7 projects through an orifice in one end of the connecting-bar 30, 55 while the pin projecting from the hinge knuckle at the top of the other bar 7 is formed with a head 35 adapted to enter the slot 32 in the plate 31 at the enlarged end 33 thereof and slide along said plate to the 60 notch 34 in said slot, which firmly holds the connecting-rod and the entire frame of the chair in its set-up position.

36 is a cover having a loop 37 formed at one end thereof, through which the connect-

ing-bar 30 extends; the cover 35 further has 65 the corner pockets 38 fitting over the meeting ends of the bars 1 and 23, as shown in Fig. 2.

This forms a very complete and comfortable chair of great stability and strength, 70 and at the same time of very light construction, as the several bars are so connected and reinforced that they can be made of very light material.

The chair may be readily folded by sliding the head 35 of the knuckle pin 22 out of the slot in the plate 31 of the connecting-bar, and removing the cover 36 from the chair. The connecting-bar 30 is then allowed to hang from the back of the chair at 80 one corner thereof, and the whole framework may be folded together, as shown in Fig. 1. This is made possible through the measured lengths of the several bars, whereby the bars 26 together with the upper portions of the bars 15 equal in length the bars 7, and similarly the bars 23 with that portion of the bars 15 below the pins 25 equal in length the bars 1.

It must be understood that the invention, 90 though herein described in connection with a chair, is equally applicable to folding tables. This would be readily accomplished by replacing the bars by bars similar to the bars 7, whereby a frame of the proper height 95 for a table would be obtained. Furthermore, the joint members used in connection with the bars 1 and 7 could be readily used for supporting the cross legs of furniture for any use adapted to be folded into a small 100 compass.

What I claim as my invention is:

1. In a foldable frame for chairs, tables or the like having a plurality of pairs of crossed bars pivotally secured one to the other intermediate of their length at their point of juncture and hinged one to the other at their extremities, of a pair of plates interposed between said pairs of crossed bars at the juncture thereof and having 110 lugs projecting therefrom at the side in contact with a bar and clamping the sides of said bars in pairs and stop lugs projecting therefrom toward the other side so that the stop lugs of one plate contact with the stop lugs of the other plate of a pair of bars when in their extended position.

2. In a foldable frame for chairs, tables or the like having a plurality of pairs of crossed bars pivotally secured one to the other intermediate of their length at their point of juncture and hinged one to the other at their extremities, of a plate of substantially S-shape on the inner side of a crossed bar at the pivotal point thereof and having a central orifice through which the pivot-pin of said cross bar extends and lugs extending from the body portion thereof in

pairs to each side of said cross bar and clamping said plate to said cross bar and stop lugs projecting from said plate on the opposite side to the aforesaid lugs and at 5 the extreme ends thereof and contacting with the stop lugs of the plate on the other bar of a pair.

Signed at the city of Ottawa, in the Province of Ontario, in the Dominion of Canada, this 5th day of October, 1909.

ALEXANDER GRANT COLE.
